D. P. HEATH

REFRIGERATING APPARATUS

Filed March 6, 1924

By

B. P. Mueller

Attorney

UNITED STATES PATENT OFFICE.

DELOS P. HEATH, OF DETROIT, MICHIGAN.

REFRIGERATING APPARATUS.

Application filed March 6, 1924. Serial No. 697,182.

To all whom it may concern:

Be it known that I, DELOS P. HEATH, a citizen of the United States, residing at Detroit, in the county of Wayne and State of Michigan, have invented a new and useful Refrigerating Apparatus, of which the following is a specification.

This invention relates to refrigerating apparatus and particularly relates to mechanical refrigerating plants.

It is an object of the invention to provide a mechanical refrigerating plant that may be compactly contained within a chamber and conveniently installed as a unit within a refrigerator.

It is a further object to provide for air-cooling of a unit so installed, and to so arrange the motor, compressor and condenser of the unit as to be acted upon and effectively cooled in common by the same cooling current of air.

In attaining these objects, the invention contemplates circulating a cooling current of air through a chamber, preferably by means of a suction fan, and locating in said chamber, the motor, compressor and condenser of the apparatus as connected and disposed in unitary relation in the path of said cooling air current, the motor and fan preferably surmounting the compressor adjacent an outlet with the condenser adjacent an inlet to said chamber, the expansion coils for the refrigerant being disposed in the cooling chamber of a refrigerator adjacent to but insulated from the first-mentioned chamber.

A preferred embodiment of the invention is hereinafter described and is illustrated in the accompanying drawing, wherein,

Fig. 1 is a view in elevation of the improved apparatus, sectionally showing a refrigerator, wherein said apparatus is installed.

Fig. 2 is a view of the same in horizontal section, the plane of section being indicated by line 2—2 of Fig. 1.

In these views the reference character 1 designates a refrigerator or the like, and 2 is a partition wall in said refrigerator, preferably of a heat-insulating nature, a refrigerating chamber 3 being formed at one side of said partition to receive food or other articles requiring cooling, and a relatively large chamber 4 being formed at the other side of said partition. Within the chamber 4, upon the bottom 5 thereof, there is

mounted a unit comprising a base 6, a refrigerant compressor 7 upon said base, a motor 8 surmounting said compressor, and a condenser 9 upon the base at one side of the compressor. The compressor is driven from the motor by a belt 10 engaging pulleys 11 and 12 upon the shafts 13 and 14 of the motor and compressor respectively. A platform 15, which carries the motor, is elevated above the outlet head 16 of the compressor by standards 17 secured to the compressor by bolts 18, one of said standards being partly broken away in Fig. 1. Upon the motor shaft is mounted fast a suction fan 19 which is disposed within a circular air outlet opening 20 in the upper rear wall of the chamber 4. The condenser 9 for the refrigerant is formed by a plurality of helical coils, having a common vertical axis, 75 said coils being mounted at one side of the compressor 7 upon a ring 22, which rests upon the base 6 surrounding a circular air inlet opening 23 in said base. Said opening passes also through the floor 5 of the chamber 4, communicating with an air duct 24, below said floor, laterally extended and having an inlet portion projecting through a wall of the refrigerator transverse to the wall having the outlet opening 20. The condenser 9 is adapted to be supplied at its upper ends with a refrigerant to be condensed through pipes 25 leading from the outlet head 16 of the compressor. The lower ends of the condenser coils are connected 80 in common with a manifold fitting 26 from which the condensed refrigerant is conducted by a pipe 27 to a boiling or vaporizing coil formed by a serpentine pipe 28 arranged within the chamber 3. From said coil 28 85 the refrigerant is returned to the compressor 7 through a pipe 29. 30 designates the usual expansion valve controlling the delivery of the refrigerant into the heat-absorbing coil 28 of the refrigerant circuit. 95

In the use of the described apparatus, the air current drawn through the chamber 4 by the fan 19, enters said chamber through the opening 23, being conducted to said opening through the refrigerator side wall 105 by the duct 24. Rising through and around the condenser coils 9, the first effect of the air current is to cool said coils. From said coils the air flows about the compressor cylinder, the head 16, and the motor 8, exercising a cooling effect upon all of said elements. Finally the air, with its accumu-

lated heat, is discharged from the chamber 4 (and from the refrigerator) through the opening 20. The superposed relation of the motor to the compressor is desirable, in the 5 interest of compactness, and also serves to arrange the hotter upper portion of the compressor and the motor substantially in the path of the cooling air current.

The unitary grouping and location of all 10 of the heat inducing parts of the plant within a single chamber, through which a cooling current of air is set up to dissipate the heat developed by operation of the plant, possesses numerous advantages aside from 15 the cooling feature, among which may be mentioned concealment of the entire plant, the avoidance of necessity for long pipe lines either to a basement or to any other of the usual exterior locations for the motor, compressor and condenser, a consequent economy of material and increase of efficiency, and a more ready portability for the refrigerator and its mechanism.

What I claim is:

- 25 1. In a refrigerating apparatus, a chamber having an air inlet in its bottom and an air outlet in its upper portion, a refrigerant condenser arranged within said chamber across said inlet, a refrigerant compressor within said chamber adjoining said condenser substantially between said inlet and outlet, a motor surmounting said compressor in driving engagement therewith, and an exhaust fan driven by said motor in line 30 with said outlet for discharging air from said chamber and inducing a flow through said inlet.
2. In a refrigerating apparatus, a chamber having an air inlet in its bottom and 35 having an air outlet, a refrigerant compres-

sor within said chamber substantially between said inlet and outlet, drive means for said compressor, means for maintaining a flow of air through said chamber from said inlet to said outlet, and a condenser for the 45 refrigerant having the form of a pipe coiled adjacent to and in substantial registration with said inlet, whereby the incoming air is sufficiently confined by the convolutions of the coiled pipe, to insure a distribution 50 of such air throughout the length of the coil.

3. In a refrigerating apparatus, a chamber having an air inlet and an air outlet, means for inducing a flow of air through said chamber from said inlet to said outlet, 55 and a refrigerant condenser within said chamber in close proximity to said inlet having the form of a coiled pipe with substantially coaxial convolutions, and having the space within said convolutions substantially registering with said inlet, whereby the incoming air flows directly axially into and through said convolutions, and is sufficiently confined thereby to insure its distribution to all of said convolutions. 60

4. In a refrigerating apparatus, a refrigerator having a chamber therein, with an air inlet in its bottom and an air outlet in one of its side walls, an air conduit having an opening in a side wall of the refrigerator 70 and having a delivery connection to said air inlet, means within said chamber for inducing a flow of air from said inlet to said outlet, and a refrigerant condensing coil within said chamber having the space within its convolutions substantially registered with 75 said air inlet.

In testimony whereof I sign this specification.

DELOS P. HEATH.
